CLAIM

The ornamental design for a vehicle wheel rim, as shown and described.

DESCRIPTION

FIG. 1 is a front perspective view if a first embodiment of a vehicle wheel rim, showing my new design;

FIG. 2 is a front perspective view of the first embodiment;

FIG. 3 is a side elevation view of the first embodiment;

FIG. 4 is a front elevation view of the first embodiment;

FIG. 5 is a rear perspective view of the first embodiment;

FIG. 6 is a rear elevation view of the first embodiment;

FIG. 7 is another front perspective view of the first embodiment;

FIG. 8 is a front perspective view of a second embodiment of a vehicle wheel rim, showing my new design;

FIG. 9 is a front perspective view of the second embodiment;

FIG. 10 is a side elevation view of the second embodiment;

FIG. 11 is a front elevation view of the second embodiment;

FIG. 12 is a rear perspective view of the second embodiment;

FIG. 13 is a rear elevation view of the second embodiment; and,

FIG. 14 is another front perspective view of the second embodiment.

The broken lines of FIGS. 1, 2, 8, and 9 illustrate the claim in use and form no part of the claimed design.

Any surfaces of the design not shown, including interior surfaces and any surfaces shown in broken lines, form no part of the claimed invention.

1 Claim, 14 Drawing Sheets
